UNITED STATES PATENT OFFICE.

THOMAS J. MAYALL, OF READING, MASSACHUSETTS.

MACHINE FOR APPLYING CEMENT AND FLOCK TO CLOTH.

SPECIFICATION forming part of Letters Patent No. 286,038, dated October 2, 1883.

Application filed March 19, 1883. (No model.)

To all whom it may concern:

Be it known that I, THOMAS J. MAYALL, of Reading, in the county of Middlesex and Commonwealth of Massachusetts, have invented a new and improved machine for applying rubber-compound fluid cement, which I call "Mayall Cement," and flock to cloth to produce a water-proof cloth, which I designate "Mayall Cloth," of which the following is a specification.

My invention relates to devices for evenly spreading the fluid cement on the surface of cloth, and for laying the flock evenly on the surface of the cement, and for pressing the flock onto and into the cement, so that it will firmly adhere, the object of the invention being to provide a convenient and economical apparatus to produce, with common cotton or linen cloth and rubber cement and flock, the water-proof cloth which I term "Mayall cloth;" and it consists in the construction and arrangement of the machine and its various parts, as hereinafter described.

In the drawings annexed, Figure 1 shows a side view of the machine containing and supporting the operating devices, and a frame or table supporting a movable roll, over and around which the cloth to be treated passes. Fig. 2 shows a top view of the machine and table with a loop of cloth in process on it. Fig. 3 shows a longitudinal section through the machine as shown in Figs. 1 and 2.

I will call the left-hand end of the machine, as shown in the drawings, the "forward" and the right-hand the "rear" end of the machine.

a is a drawing-pulley on the end of the shaft which passes through the main roll in the machine, by which the cloth is moved forward during the process.

a' is the shaft on which the drawing-pulley *a* and the main roll and the gear and pulley actuating the pressure-roll and the brushing-roll are supported.

45 *a*² is the main roll of the machine, by which the cloth is moved forward.

*a*³ is a pulley on the shaft *a'*, over which a belt passes, which moves the brush-roll.

40 *a*⁴ is a belt from and over the pulley *a*³ and the pulley on the shaft of the brush-roll.

*a*⁵ is a pressure-roll, with a counterpart un-

der it, between which the cloth passes after the flock has been deposited on it.

*a*⁶ is the brush-roll.

*a*⁷ is a gear on the shaft *a'*.

*a*⁸ is an intermediate gear between the gear *a*⁷ and the gear on the end of the pressure-roll *a*⁵.

*a*⁹ is a gear on the end of the pressure-roll *a*⁵.

e is a knife with straight edge, extending across and supported by standards on each side of the machine, against the edge of which, and at right angles to it, the cloth is drawn forward to evenly spread the cement upon it.

e' is a trough under the knife *e* and below the cloth, extending across the machine and resting on the frame of it, into which any fluid cement which may run over the edge of the cloth will fall.

*e*² is a roll below and a little to the rear of the brush-roll, over which the cloth passes, the purpose of it being to keep the cloth up close to the under side of the brush-roll.

*e*³ is a supporting-roll at the rear of the knife *e*, over which the cloth moves, its purpose being to keep the cloth up to the edge of the knife, so that it will scrape the surface of the cloth and evenly distribute the fluid cement on the surface of it.

*e*⁴ is a roll mounted on a shaft which is supported in movable or sliding bearings resting on the frame of the table, so that the roll may be moved forward and backward on the machine, as circumstances may require, and over and around which the loop of cloth in process passes.

*e*⁵ is a roll with a crank to turn it, and cords which wind up on it by turning it, which are attached to arms extending from the roll *e*⁴, so that by turning this roll by the crank the roll *e*⁴ is drawn toward the rear end of the machine, the purpose of this being to give greater or less tension to the loop of cloth in the machine while in process.

*e*⁶ is a loop of cloth extending over and around the main roll *a*², the ends of the cloth being joined by cement or otherwise, so as to make a loop or link of it. This loop of cloth passes between the pressure-rolls *a*⁵, under the brush-roll *a*⁶, over the supporting-pulley *e*², under the edge of the knife *e*, over the trough *e'* and the supporting-roll *e*³, and over and

around the roll e^4 , and forward below all the rolls to the roll a^2 , moving, when the machine is operating, in the direction indicated by the arrow x .

e^1 is a trough extending across the machine, and supported at each end on frames resting on the side frames of the machine, having a funnel-shaped bottom with openings through it. The fluid cement to be spread upon the cloth is put into this trough. The openings are so graduated that a sufficient quantity of the fluid cement will pass through onto the upper surface of the cloth to be covered by it, and they can be wholly closed at pleasure.

e^3 is a trough similar to the trough e^1 , into which the flock to be deposited on the cement-covered cloth below is placed, in the bottom of which are suitable openings to permit the flock to fall through onto the cloth below. In the bottom of this trough a device for stirring the flock to make it fall uniformly may be placed, if necessary.

The operation of the machine is this: A piece of suitable cloth is cut long enough to reach around the main roll a^2 and the roll e^1 , and put around these rolls, and the ends joined by cement or otherwise. The proper degree of tension is given to the cloth by turning the crank of the roll e^1 and fastening it at the right point. Fluid cement is placed in the trough e^1 . Flock is placed in the trough e^3 . The rolls are put in motion, carrying the loop of cloth toward and around the main roll at the forward end of the machine. The fluid cement falls on the cloth, and as it passes under the knife it is evenly distributed by it over the whole width, the knife-edge so pressing against the upper surface of the cloth that all the surplus cement, after giving the cloth the thinnest possible coating, is retained at the rear of the knife, and as the quantity accumulates behind the knife it falls over the edge of the cloth into the trough e^3 . When the surface of the cloth covered with cement comes under the trough of flock, the passages through the bottom of it are opened and the flock is made to fall from it upon the whole width of the cloth. As the cloth is carried still farther forward the brush-

roll evenly distributes the flock on the cemented surface of the cloth and rubs it against 50 and into the cement. This surplus will fall into a suitable receptacle prepared to receive it under the machine, and from time to time returned to the trough from which it fell. As the motion of the machine continues the cemented and flocked surface of the cloth comes under the pressure-roll a^5 , which, acting by 55 quantity or springs, as the case may be, presses the flock against and into the cement on the cloth. When the whole loop of cloth has been 60 treated in this way, it should be carefully examined with a magnifying-glass, and if it is found that the cement can be seen above the flock it should be again run around, while the cement-trough is closed and another dressing 65 of flock deposited on it and pressed in by the roll, as before, when it will be found that the cement will be completely covered by the flock. The loop of cloth will then be removed and placed in a suitable place to dry, and when the 70 cement is dried it will be ready for use or sale.

It is not necessary to cure the rubber or cloth treated as described with the Mayall cement by sun or artificial heat, as has been necessary with what has been termed "gossamer rubber 75 cloth," the character of the Mayall cement, derived from its component substances, rendering that unnecessary, while at the same time its superior strength and adhesive tenacity and pliability make the completed product, which I term "Mayall cloth," indestructible by ordinary wear and fair usage. It will 80 of course tear if sufficient force is applied; but it will resist much more than the ordinary rubber-coated cloth, or "gossamer," as it is called. 85

I claim as new and of my invention—

The above-described improved machine for applying and affixing cement and flock to cloth, consisting of the rolls a^2 , a^3 , a^4 , e^2 , e^3 , e^4 , and e^5 , the knife e , and the troughs e^1 and e^3 , in combination with suitable supporting and driving devices, all substantially as set forth. 90

THOS. J. MAYALL.
